(57) **CLAIM**

The ornamental design for a module for flat cables, as shown and described.

DESCRIPTION

FIG. 1 is a front view of a first embodiment of a module for flat cables.

FIG. 2 is a rear view of the module of FIG. 1.

FIG. 3 is a top view of the module of FIG. 1.

FIG. 4 is a bottom view of the module of FIG. 1.

FIG. 5 is a first side view of the module of FIG. 1.

FIG. 6 is a second side view of the module of FIG. 1.

FIG. 7 is a perspective view of the module of FIG. 1 showing the front, top, and first side.

FIG. 8 is a front view of a second embodiment of a module for flat cables.

FIG. 9 is a rear view of the module of FIG. 8.

FIG. 10 is a top view of the module of FIG. 8.

FIG. 11 is a bottom view of the module of FIG. 8.

FIG. 12 is a first side view of the module of FIG. 8.

FIG. 13 is a second side view of the module of FIG. 8; and, FIG. 14 is a perspective view of the module of FIG. 8 showing the front, top, and first side.

In the Figures, the curved inner regions form gaps constructed to receive a male plug member. The gaps are shown by single lines in FIGS. 1-7 and by pairs of lines in FIGS. 8-14.

1 Claim, 8 Drawing Sheets
